UNITED STATES PATENT OFFICE

GEORGE J. BLUM, OF CHICAGO, ILLINOIS

DESIGN FOR A VERTICAL EXTENSION DEVICE FOR AUTOMOBILE BUMPERS

Application filed February 6, 1933. Serial No. 47,128. Term of patent 7 years.

To all whom it may concern:

Be it known that I, GEORGE J. BLUM, a citizen of the United States, residing at Chicago, in the county of Cook and State of Illinois, have invented a new, original, and ornamental Design for a Vertical Extension Device for Automobile Bumpers.

In the drawing:

The design is especially characterized by an intermediate portion curved to conform substantially to the transverse curvature of the main bumper bar when applied thereto, and reversely curved end portions substantially as shown.

I claim:

The ornamental design for a vertical extension device for automobile bumpers, substantially as shown and described.

GEORGE J. BLUM.
